UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

967,885.

Specification of Letters Patent. Patented Aug. 23, 1910.

Application filed March 10, 1910. Serial No. 548,448.

To all whom it may concern:

Be it known that I, CHARLES E. DAVIS, a citizen of the United States, residing at Chicago, in the county of Cook and State 5 of Illinois, have invented a certain new and useful Improvement in Mining-Machines, of which the following is a specification.

This invention relates to mining machines, and has for its object to provide a new and improved cutter head for machines of this 10 description.

The invention is illustrated in the accompanying drawings, wherein—

Figure 1 is a plan view showing a cutter 15 head embodying the invention; Fig. 2 is a section taken on line 2—2 of Fig. 1; Fig. 3 is a sectional view taken on line 3—3 of Fig. 1.

Like numerals refer to like parts throughout the several figures.

This invention is particularly adapted for mining machines having a chain cutter which moves along the face of the coal, and which is supported by the cutter head. This 25 cutter head, as shown in the drawings, is formed of two plates, a top plate 1 and a bottom plate 2, removably connected together. These plates are provided with projecting parts 3 and 4, which form between them the cutter chain receiving space 5 for the cutter chain. Connected with the 30 projecting parts 3 and 4 are the lips or chain guiding pieces 6, which are preferably made of tool steel riveted and welded to the top and bottom plates. These lips are subject to great wear, and hence should be hard and should be rigidly fastened in place. At the back of the chain receiving space there are provided removable wearing plates 7. 35 Between the lips 6 and the plates 7 are grooves or guideways for receiving projecting portions or guides formed on the cutter chain so that said cutter chain will be securely held in place as long as the top and bottom plates are firmly held together. 45 Some suitable means is provided for holding the top and bottom plates 1 and 2 firmly together.

In view of the fact that the device is 50 used under conditions where dust and dirt are liable to get between the plates, it is desirable to have some means whereby the plates cannot be fastened together until their opposed faces are thoroughly cleaned of all 55 foreign material so that when placed to-

gether they will be in proper position and in actual contact, and so that they will be held solidly together. This result is secured by means of one or more holding pieces 9, which, as herein shown, consist of wide, flat 60 metal pieces. The top plate is provided with a projecting part 10 provided with a locking piece 11, and the bottom plate has connected therewith a locking piece 12. The holding piece 9 is forced in between the locking 65 pieces 11 and 12, one end engaging the locking piece 11, and the other end resting upon a support to which it is fastened by the cap screw 13. These pieces are preferably arranged so that there will be just space 70 enough between them to receive the holding piece when all foreign material is removed from between the engaging faces of the top and bottom plates, and hence it will be seen that the two plates cannot be assembled 75 until these faces are clean. The holding pieces are then forced into position, as shown in Figs. 1 and 2, and securely lock the top and bottom plates together. These holding pieces are held in any desired manner against 80 accidental removal, as by means of the cap screws or bolts 13. It will thus be seen that the solid clamping of the top and bottom plates in no manner depends upon the tightness with which the bolts 13 are screwed 85 down. At each corner of the cutter head there is provided a sprocket wheel 14. Bolts 15 pass through these sprocket wheels. Said bolts are preferably provided with a fine thread and with heads so that they can be 90 engaged by a wrench. They help hold the top and bottom plates together, and by making the thread fine, the proper holding of these plates together at the corners is secured.

By means of this construction the point, at which the two plates are held together, that is, the point where the separating strain between the plates due to the action of the cutter chain is resisted, is brought close up 100 to the chain, and this point is brought much closer to the chain than is possible by means of bolts or other similar fastening devices. The importance of this construction will be seen when it is noted that during the operation of the mining machine there is exerted a pressure by the cutters which tends to force the top and bottom plates apart, and that the lever arm by means of which this force is exerted is made comparatively 110

short, and the effect of the force therefore greatly reduced.

It will be noted that in this construction the holding or fastening piece is substantially parallel to the top and bottom plates, and that it engages faces substantially parallel to these plates. It will further be noted that the holding device has two engaging faces, one of which engages an engaging face associated with the upper plate and the other an engaging face associated with the lower plate, and that all of these engaging faces are substantially parallel and are also substantially parallel to the portions of the top and bottom plates between which the chain is received.

I claim:

1. A cutter head for mining machines comprising a top and bottom plate arranged with a chain receiving space between them each plate having a projection, a holding piece engaging each projection and said holding piece being substantially parallel with said plates.

2. A cutter head for mining machines comprising two opposed plates with engaging faces each having a projecting part, the projecting parts forming between them a space for a cutter chain, a holding piece for holding said plates together and substantially parallel to said plates, locking parts on said plates between which said holding piece is received.

3. A cutter head for mining machines comprising two opposed plates with engaging faces each having a projecting part, the projecting parts forming between them a space for a cutter chain, a holding piece for holding said plates together and substantially parallel to said plates, locking parts on said plates between which said holding piece is received, the locking part on the upper plate located below the locking part on the lower plate when the holding piece is in position.

4. A cutter head for mining machines comprising two opposed plates with engaging faces each having a projecting part, the projecting parts forming between them a space for a cutter chain, a holding piece for holding said plates together and substantially parallel to said plates, locking parts on said plates between which said holding piece is received, the locking part on the upper plate located below the locking part on the lower plate when the holding piece is in position, the locking parts on the top and bottom plates being so spaced with relation to each other that the engaging faces of the plates must be in contact before the holding

piece can be inserted between said locking parts.

5. A cutter head for mining machines comprising two plates adapted to be fastened together and having opposed faces, 65 projections on said plates arranged to form between them a receiving space for a cutter chain, a sprocket wheel between said plates at each corner of the cutter head, a locking part on each plate projecting beyond the 70 locking part of the other so that they pass each other during the process of assembling, and a holding piece adapted to be forced between said locking parts.

6. A cutter head for mining machines 75 comprising separable top and bottom plates having a space between them for receiving a cutter chain, a holding piece for fastening the plates together, said holding piece being substantially parallel to said plates, a locking part on each of said plates, the holding piece passing between the locking parts, the adjacent vertical faces of said locking parts being in substantially the same vertical plane.

7. A cutter head for mining machines comprising two plates adapted to be fastened together, projections on said plates arranged to form between them a receiving space for a cutter chain, a locking part on 90 each plate, the locking part on one plate projecting beyond the locking part on the other plate when the plates are in their operative position, and a connecting piece engaging both locking parts.

8. A cutter head for mining machines comprising a top and bottom plate arranged with a chain receiving space between them, a device for holding said plates together, having a locking element substantially parallel with the exterior faces of the portions of the plates between which the chain is received and locking projections connected with said plates between which said locking element passes.

9. A cutter head for mining machines comprising a top and bottom plate arranged with a chain receiving space between them, a part on each of said plates back of said chain receiving space, each part provided with an engaging face, one an upper and the other a lower engaging face and a unitary holding piece engaging both of said parts and making contact with both of said engaging faces.

CHARLES E. DAVIS.
